RECTIFIER PROTECTIVE SYSTEM

Othmar K. Marti, Wauwatosa, Wis., assignor to
 Allis-Chalmers Manufacturing Company, Mil-
 waukee, Wis., a corporation of Delaware

Application August 20, 1932, Serial No. 629,663

10 Claims. (Cl. 175—363)

This invention relates to improvements in protective systems and more particularly to protective systems for electron discharge devices of the arcing type.

It is well known that proper operation of electron discharge devices is obtained only when gas or vapor within such device is maintained within certain limits of pressure. In devices of the vacuum type, the space should be highly evacuated and, in devices of the gas or vapor type, the gas or vapor should be maintained at a pressure not exceeding a predetermined value. The presence of undesired gases or vapors or the occurrence of undesired pressures in the operating gas or vapor are not readily detected because the pressure within the device is not uniform, consequently a pressure gage connected at one point of the device gives no indication of the pressures at other points thereof. The indications of pressure gages are particularly deficient during the so-called forming or seasoning of gas or vapor arcing devices, when large amounts of gas are evolved from the different parts of the device and more particularly from the electrodes thereof. The degree to which a device of the above character is seasoned is determined by the amount of gas evolving from the electrodes, and the proper operation of such device is determined by the pressure in the path of discharge where it is usually difficult or entirely impossible to insert a pressure measuring device. Under the influence of some accidental factors, electron discharge devices are also apt to fail in their valve action whereupon an internal short circuit or backfire occurs. Means have been heretofore developed for interrupting such backfires shortly after the occurrence thereof so as to minimize their destructive effect on the electrodes and their disturbing effect on the system connected therewith. Such means, however, do not detect impending backfires and hence cannot prevent their occurrence.

It has been found that, in a device of the gas or vapor type, when the pressure in the space within the device is different from that at which satisfactory operation may be expected, the discharge or arc becomes unstable and introduces a rapidly varying resistance in the circuit of the device. Such variations of the resistance in the circuit produce oscillations at different frequencies including modulated oscillations within the range of frequency used for radio broadcasting purposes. Such oscillations in turn produce electromagnetic waves which may be detected in the immediate vicinity of the device. It was also

found that, before an electron discharge device backfires, the arc also oscillates for a short period of time and likewise leads to the production of electromagnetic waves. It should not be concluded that backfires are due solely or even partially to the presence of foreign gases within the device, as they may be due to some other cause also leading to the production of oscillations. By introducing such oscillations into the input circuit of a radio receiving set, it is possible to obtain currents from the output circuit of such set which give an indication of any disturbance and permit disconnection of the device before a backfire has occurred as a result of such disturbance.

It is accordingly one object of the present invention to provide a control system for electron discharge devices in which oscillations in the circuit of the device may be detected, amplified and transformed into audible or visible signals.

Another object of the present invention is to provide a control system for electron discharge devices in which undesired values of the gas or vapor pressure within the device are measured by means of the magnitude of oscillations in the circuit of the device.

Another object of the present invention is to provide a control system for electron discharge devices in which disturbances leading to backfires within the device are detected through measurement of oscillations in the circuit of the device.

Another object of the present invention is to provide a control system for electron discharge devices in which the device is automatically made inoperative upon occurrence of oscillations in the circuit thereof.

Objects and advantages other than those above set forth will be apparent from the description when read in connection with the drawing, in which:

Fig. 1 diagrammatically illustrates one embodiment of the present invention applied to an electron discharge device of the metallic vapor arcing type operable as an electric current rectifier, in which a radio receiving set is used for measuring the oscillations within the device and for disconnecting such device upon occurrence of oscillations of a predetermined value;

Fig. 2 diagrammatically illustrates a modified embodiment of the present invention differing from that shown in Fig. 1 in the means used for making the electron discharge device inoperative upon the occurrence of oscillations above a predetermined limit in the circuit thereof.

Referring more particularly to the drawing by

characters of reference, reference numeral 6 designates an electron discharge device of the metallic vapor arcing type shown as connected for alternating current rectification, between an alternating current supply line 7 and a direct current output line 8, 9. Device 6 is connected with line 7 by means of a transformer having a primary winding 11 and a secondary winding 12 comprising a plurality of star connected portions severally connected with the anodes 13 of device 6. As shown in Fig. 1, winding 11 is connected with line 7 by means of a circuit breaker 14 maintained in the closed position by means of a latch 16 which may be released upon energization of a trip coil 17. One of the conductors of the output line is provided with a second circuit breaker 18 maintained in its closed position by a latch 19 which may be released upon energization of a trip coil 21. Trip coils 17 and 21 may be energized from a battery 22 having its circuit completed over contacts 23 upon closure of a relay 24 connected as will be described hereinafter.

The oscillations in the circuit of the device are transmitted to the input circuit of a radio receiving set of a suitable type generally represented at 27. Such transmission is obtained by electrostatic or electromagnetic coupling means between the circuit of the device and the input circuit of the receiver set such as a transformer 26. Receiving set 27 is shown as comprising a set of filters 28 for the purpose of transmitting, through the circuits of the set, oscillations of only one frequency or only within a predetermined range of frequencies. The receiving set is shown as also comprising one stage of radio frequency amplification 29, a detector 31 and one stage of audio frequency amplification 32. The output terminals of the receiving set may be connected with a number of control devices such as relay 24, an ammeter 33 and a loud speaker or horn 34. The device 6 may be evacuated or maintained at any predetermined pressure by a suitable pump 36.

In operation, assuming that line 7 is energized and that circuit breakers 14 and 18 are closed, anodes 13 will sequentially carry current received from line 7 for rectification into direct current supplied to line 8, 9 as is well known in the art. Upon the occurrence of disturbing pressures within the device or of any other phenomena apt to produce backfires therein, the circuit of the device will oscillate. Such oscillations will generally be at frequencies within the range of the frequencies used for radio broadcasting purposes, modulated at frequencies within the audible range of frequencies. Such oscillations induce currents in transformer 26 and are transmitted to filter 28. Filter 28 permits application of voltages at one frequency or within a predetermined range of frequencies to audio amplifier 29 where such oscillations are amplified to be further transformed into audio frequency oscillations in detector 31, such oscillations then being amplified in amplifier 32 with the result that currents at such audio frequencies are supplied to meter 33, relay 24, and audible signal 34. Meter 33, therefore, continuously gives a visible indication of the amplitude of the oscillations within device 6, and signal 34 gives a continuous audible indication thereof. Such oscillations may reach a value causing the production of excessive losses within the device or may be conducive to the occurrence of backfires, whereupon relay 24 closes its contacts 23, thereby energizing trip coils 17 and 21 and opening circuit breakers 14 and 18. If the oscillations in the device were caused by the

presence of excessive amounts of gas therein, the circuit breakers may be reclosed only after such gases have been removed by means of pump 36. If the disturbance is produced by some transient accidental cause, the device may generally be reconnected immediately with lines 7 and 8, 9.

In the embodiment shown in Fig. 2, device 6 is provided with control electrodes 36 for purposes of controlling the operation of the several anodes 13 thereof. Control electrodes 36 receive a negative potential with respect to the cathode of the device from a battery 37 and also receive alternating potentials from secondary winding 39 of a transformer having a primary winding 41 energized from line 7. Control electrodes 36 thus sequentially receive positive potentials with respect to the cathode, thereby permitting operation of the associated anodes 13. As is well known in the art such connection permits regulation of the output voltage of the device. Resistances 38 are inserted in the circuits of control electrodes 36 to limit the flow of current therethrough. Winding 41 is connected with line 7 by means of a circuit breaker 42 retained in its closed position by latch 43 which may be released upon energization of a trip coil 44. Trip coil 44, in the present embodiment, is shown as operable from battery 22 through contacts 23 of relay 24 while circuit breakers 14 and 18 are provided only for manual operation. In the present embodiment, the input circuit of radio receiver 27 is shown connected with an antenna 30 extending into the casing of device 6, and with a ground as at 35.

In operation, device 6 operates as in the embodiment of Fig. 1, the sequential energization of anodes 13, however, being controlled by the energization of control electrodes 36. Upon occurrence of a disturbance within device 6, oscillations are produced therein and transmitted by means of antenna 30 to the input circuit of radio receiver 27. In the present embodiment also audio frequency currents are obtained and are supplied to meter 33, relay 24, and loud speaker 34. When such currents reach a predetermined magnitude, relay 24 closes its contacts 23 thereby causing circuit breaker 42 to disconnect winding 41 from line 7. Winding 39 no longer being energized from winding 41, all control electrodes 36 receive only a negative potential from battery 37, thereby causing device 6 to cease to function. If the disturbance was caused by the presence of foreign gases in the device, such gases must be removed by pump 36 whereupon circuit breaker 42 may be reclosed to permit further operation of the device. If the oscillations were produced due to some transient accidental cause, circuit breaker 42 may generally be reclosed immediately after its opening.

It will be understood by those skilled in the art that although the present protective system is illustrated only as applied to electron discharge devices connected for operation as electric current rectifiers, such system may be applied without modifications of its essential parts to such devices when operable as direct current inverters, D. C. voltage converters, frequency converters or circuit interrupters.

Although but two embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In a protective system for electron discharge devices, an alternating current line, a transformer connected with said line, an electron discharge device of the arcing type connected with said transformer and subject to creation of high frequency oscillations therein upon occurrence of abnormal conditions therein, a direct current line connected with said transformer and with said device, and indicating means inductively connected with said direct current line operable responsive to and in dependence upon the occurrence of said high frequency oscillations within said device.

2. In a protective system for electron discharge devices, an alternating current line, a transformer connected with said line, an electron discharge device of the arcing type connected with said transformer, a direct current line connected with said transformer and with said device, and a radio receiving set coupled with said device for detecting and indicating oscillations occurring in said device upon the occurrence of conditions tending to cause disturbances therein.

3. In a protective system for electron discharge devices, a plurality of electric current lines, an electron discharge device of the arcing type, a plurality of circuit breakers controlling the connection of said device with said lines, means for detecting and amplifying the occurrence of oscillations in said device tending to cause the occurrence of disturbances therein, and means operated by the first said means to cause operation of said circuit breakers.

4. In a protective system for electron discharge devices, a plurality of electric current lines, an electron discharge device of the arcing type, a plurality of circuit breakers controlling the connection of said device with said lines within a predetermined range of frequencies, means for detecting and amplifying the oscillations produced in said device and tending to cause the occurrence of disturbances therein, and means operated by the first said means to cause operation of said circuit breakers.

5. In a protective system for electron discharge devices, a plurality of electric current lines, an electron discharge device of the arcing type, a plurality of circuit breakers controlling the connection of said device with said lines, magnetic means associated with each of the said circuit breakers to control the opening thereof, a source of current arranged for connection with said magnetic means, means for detecting and amplifying oscillations produced in said device and tending to cause the occurrence of disturbances therein, and a relay operated by the second said means to control the connection of said source of current with said magnetic means upon the occurrence of oscillations within a predetermined range within said device.

6. In combination with a vapor electric valve converting apparatus comprising an anode, a cathode, a control electrode, and a conductive

member in contact with the ionized vapor of the apparatus, a control transformer for exciting said control electrode to control the energy transmitted by said apparatus, and means responsive to the potential between said conductive member and said cathode for modifying the magnetization of said transformer to modify the operation of said apparatus.

7. The combination with an electric valve comprising a casing forming an evacuated chamber having an anode and a cathode supported therein and forming spaced electrodes for the flow of current of unidirection therebetween, of a control electrode associated with said anode, means for exciting said control electrode to control the said flow of current, and means comprising a conductive member supported within said casing within the ionized vapor therein operable responsive to an abnormal condition within said valve, for controlling the operation of the first said means.

8. The combination with an electric valve comprising a casing forming an evacuated chamber having an anode and a cathode supported therein and forming spaced electrodes for the flow of current of unidirection therebetween, of a control electrode associated with said anode, means comprising a transformer for exciting said control electrode to control the said flow of current, and means comprising a conductive member supported within said casing within the ionized vapor therein operable responsive to an abnormal condition within said valve, for controlling the operation of the first said means.

9. The combination with an electric valve of 35 the vapor type comprising a casing forming an evacuated chamber having an anode and a cathode supported therein and forming spaced electrodes for the flow of current of unidirection therebetween, of a control electrode associated 40 with said anode, means for exciting said control electrode to control said flow of current, means comprising a relay operable to control the first said means, and means comprising a conductive member supported within said casing in contact 45 with the ionized vapor therein operable responsive to an abnormal condition within said valve, for controlling the operation of the second said means.

10. The combination with an electric valve 50 comprising a casing forming an evacuated chamber having an anode and a cathode supported therein and forming spaced electrodes for the flow of current of unidirection therebetween, of a control electrode associated with said anode, 55 means for exciting said control electrode to control the said flow of current, and means comprising a conductive member supported within said casing within the ionized vapor therein operable responsive to an abnormal condition within said valve tending to cause reverse direction 60 of flow of said current, for controlling the operation of the first said means.
